CLAIM

The ornamental design for an operation panel, as shown.

DESCRIPTION

FIG. 1 is a perspective view of our design for an operation panel of the present invention;

FIG. 2 is a front view thereof;

FIG. 3 is a rear view thereof;

FIG. 4 is a top plan view thereof;

FIG. 5 is a bottom plan view thereof;

FIG. 6 is a right side elevational view thereof; and,

FIG. 7 is a left side elevational view thereof.
